[57] CLAIM

The ornamental design for a sign, substantially as shown and described.

DESCRIPTION

FIG. 1 is a rear perspective view of a sign showing my new design;

FIG. 2 is a front perspective view thereof;

FIG. 3 is a top plan view, the bottom plan view being identical thereto;

FIG. 4 is a right end view, the left end view being identical thereto;

FIG. 5 is a rear perspective view of a sign showing a second embodiment of my new design;

FIG. 6 is a front perspective view of such second embodiment;

FIG. 7 is a top plan view of such second embodiment, the bottom plan view being identical thereto;

FIG. 8 is a right end view of such second embodiment, the left end view being identical thereto;

FIG. 9 is a rear perspective view of a sign showing a third embodiment of my new design;

FIG. 10 is a front perspective view of such third embodiment;

FIG. 11 is a top plan view of such third embodiment, the bottom plan view being identical thereto;

FIG. 12 is a right end view of such third embodiment, the left end view being identical thereto;

FIG. 13 is a rear perspective view of a sign showing a fourth embodiment of my new design;

FIG. 14 is a front perspective view of such fourth embodiment;

FIG. 15 is a top plan view of such fourth embodiment, the bottom plan view being identical thereto;

FIG. 16 is a right end view of such fourth embodiment, the left end view being identical thereto;

FIG. 17 is a rear perspective view of a sign showing a fifth embodiment of my new design;

FIG. 18 is a front perspective view of such fifth embodiment;

FIG. 19 is a top plan view of such fifth embodiment, the bottom plan view being identical thereto;

FIG. 20 is a right end view of such fifth embodiment, the left end view being identical thereto;

FIG. 21 is a rear perspective view of a sign showing a sixth embodiment of my new design;

FIG. 22 is a front perspective view of such sixth embodiment;

FIG. 23 is a top plan view of such sixth embodiment, the bottom plan view being identical thereto;

FIG. 24 is a right end view of such sixth embodiment, the left end view being identical thereto;

FIG. 25 is a rear perspective view of a sign showing a seventh embodiment of my new design;

FIG. 26 is a front perspective view of such seventh embodiment;

FIG. 27 is a top plan view of such seventh embodiment, the bottom plan view being identical thereto;

FIG. 28 is a right end view of such seventh embodiment, the left end view being identical thereto;

FIG. 29 is a rear perspective view of a sign showing an eighth embodiment of my new design;

FIG. 30 is a front perspective view of such eighth embodiment;

FIG. 31 is a top plan view of such eighth embodiment, the bottom plan view being identical thereto; and

FIG. 32 is a right end view of such eighth embodiment, the left end view being identical thereto.

UNITED STATES PATENT AND TRADEMARK OFFICE
CERTIFICATE OF CORRECTION

PATENT NO. : Des. 273,596
DATED : April 24, 1984
INVENTOR(S) : Waldecrantz

It is certified that error appears in the above-identified patent and that said Letters Patent are hereby corrected as shown below:

On the title page:

Before the paragraph headed CLAIMS, insert the following paragraph:

-- The broken lines included in the perspective views of each embodiment are intended to indicate indeterminate length. The top view of each embodiment is shown fragmentarily for ease of illustration. --

Signed and Sealed this

Eighteenth Day of September 1984
